Filed Feb. 28, 1958, Ser. No. 49,855

Term of patent 14 years

(Cl. D80—11)

Fig. 1.

Fig. 6.

Fig. 2.

Fig. 3.

Fig. 7.

The dominant features of the design reside in the portions shown in full lines.

I claim:

The ornamental design for an island type refrigerated display case, substantially as shown and described.
